UNITED STATES PATENT OFFICE.

WILEY W. FULLERTON AND LELAND R. FULLERTON, OF POMONA, CALIFORNIA.

EXTENSION STEP FOR CARS.

Application filed February 2, 1927. Serial No. 165,337.

This invention relates to extension steps, but more particularly to extension steps for railway passenger cars, and it is an object of this invention to provide a step which 5 may be applied to the platform of a moving vehicle, which step may be lowered for use when the car is at a standstill loading or unloading passengers, and which may be folded into a position out of the way when 10 the vehicle is in motion. Most railway cars are provided with a platform step assembly having two or three steps, the lower of which is nearly always a considerable distance from the ground or platform, and 15 when passengers embark or disembark, it is necessary to provide means whereby the passengers may readily reach the lower step of the assembly. Toward this end the Pullman porters are provided with a small 20 portable stool which, when not in use may be stored within the car, but when in use is placed directly below the lower step, thereby enabling passengers to safely enter or leave the car. In addition to these stools being 25 a source of considerable expenditure for the railway or Pullman companies, they are quite inconvenient as they occupy considerable space within the car, and as they are extremely apt to become lost or broken. In 30 addition to this, when the Pullman porter is busy unloading the passengers' baggage and personal effects, the placing of a stool beneath the lower step requires an additional trip to the interior of the car for him. Furthermore, it often happens that without warning, 35 the engineer of the train is liable to pull the engine ahead a few feet or back the same up a few feet and the stool resting on the ground must again be moved to a 40 position below the step. This is another addition to the work of the Pullman porter.

It is an object of our invention therefore, to provide a pivoted extension step which 45 may be pivoted to the lower step of the platform step assembly, and which is a permanent element of the same.

A second object of our invention is to provide a step which is strong and durable, which is not apt to become damaged, and 50 which may be folded out of the way when the same is not in use, and which is well adapted to perform the services required of the same.

Another object of our invention appears 55 by virtue of the fact that tramps, hobos

and other non-paying passengers very often find it convenient to locate themselves on the step assembly beneath the shelter of the platform where they may rest securely until the train comes to a stop.

Still another object of our invention therefore, is to provide a pivoted step which when folded upon the platform assembly, occupies nearly all the space between the platform assembly and the platform, thereby preventing the use of such space illegitimately for riding.

With the foregoing and other objects in view, which will be made manifest in the following detailed description and specifically pointed out in the appended claims, reference is had to the accompanying drawings for an illustrative embodiment of the invention, wherein:

Figure 1 is a rear view of a railway vehicle showing a pair of extension steps embodying the principles of our invention applied thereto.

Figure 2 is a side view of a railway vehicle showing our improved step applied thereto in extended position.

Figure 3 is a perspective view of our extension step as applied to the platform step assembly, and

Figure 4 is a sectional view taken along the plane 4—4—4'—4' of Figure 3.

Referring to the accompanying drawings wherein similar reference characters designate similar parts throughout, a railway vehicle is designated at V. This railway vehicle is provided with a plurality of door sill structures or platform step assemblies 1, each of these assemblies being shown in the drawings as having two steps 2 and 3 and a platform 4. These steps are of the conventional type and are secured to suitable side pieces 5 and 6 respectively. Our extension step is designated generally at 10 and comprises a pair of side pieces 11 and 12 and a step 13 connecting these side pieces at their lower end, and a back 13' also connecting the side pieces and extending therebelow as at 25. These side pieces are preferably triangular in shape as shown in Figure 3, and these triangular pieces, together with the actual step form a structure that in longitudinal cross section is U-shaped. The upper ends of the triangular side pieces are provided with apertures 14, and the lower step 2 of the platform step assembly is pro-

- vided with a pair of cut-out portions 15 and 16, and a pair of pins 17 and 18 are adapted to extend through the side pieces 5 and across the cut-out portions, and the apertures 5 of the side pieces 11 and 12 are adapted to receive the pins 17 and 18 whereby the step assembly 10 may be pivoted to the platform assembly 1. The upper end of the side pieces 11 and 12 are furthermore provided 10 with cut-out portions 19 and 20, said cut-out portions providing abutments 21 (concealed) and 22. These abutments are adapted to bear against the lower side of the step 2 when the extension step is extended, whereby 15 the step may be rigid when pressure is applied to the same. Of course, it will be understood that the dimensions of the extension step may be varied to accommodate different sizes of platform step assemblies. 20 The back 13' may be so designed as to extend perpendicular to the ground or at an angle thereto. The flange 22 will of course, be so arranged that the step 13 will, when extended, be substantially parallel to the 25 steps 2 and 3, and the entire step extension when not in use may be swung upon the pins 17 and 18, so that the same will rest upon the step 2 and substantially fill the space between the platform step assembly and the 30 platform, thus preventing passengers from riding on the steps when the vehicle is in motion. The back piece 13' together with the extension 25, extends across the blinds as shown in Figure 1, and completely closes 35 the same when the device is not in use. It will be understood that various changes in the detail of construction may be made without departing from the spirit or scope of the invention as defined by the appended 40 claims.

We claim:

1. The combination with a structure having inclined side members bearing stationary steps therebetween, a platform to which the upper edges of said side members are secured, of an extension step comprising a bottom piece and a pair of side pieces rigidly attached thereto and extending upwardly therefrom, apertures in the upper ends of said side pieces, flanges adjacent said apertures, pivot pins extending through said door sill structure and receivable in said apertures, an inclined back connecting said side pieces and extending below the same whereby said extension steps may be suspended in rigid 45 relationship with respect to said structure and beneath same, or may be swung upwardly to rest against the stationary steps and to form a cover therefor.
2. The combination with a structure having inclined side members bearing stationary steps therebetween, a platform to which the upper edges of said side members are secured, of an extension step comprising a bottom piece and a pair of side pieces rigidly attached 50 thereto and extending upwardly therefrom, apertures in the upper ends of said side pieces, flanges adjacent said apertures, pivot pins extending through said door sill structure and receivable in said apertures, an inclined back connecting said side pieces and extending below the same whereby said extension step may be suspended in rigid 55 relationship with respect to said structure and beneath same, or may be swung upwardly to rest against the stationary steps and to form a cover therefor.

In testimony whereof we have signed our names to this specification,

WILEY W. FULLERTON,
LELAND R. FULLERTON.
